UNITED STATES PATENT OFFICE.

JAMES HIPKINS McNEILL, OF MINERAL CITY, VIRGINIA.

DESIGN FOR A PUZZLE-CASE.

SPECIFICATION forming part of Design No. 29,495, dated October 18, 1898.

Application filed September 13, 1898. Serial No. 690,893. Term of patent 7 years.

To all whom it may concern:

Be it known that I, JAMES HIPKINS MCNEILL, a citizen of the United States, residing at Mineral City, in the county of Louisa 5 and State of Virginia, have invented and produced a new and original Design for a Puzzle-Case, of which the following is a specification, reference being had to the accompanying drawings, forming a portion thereof, in 10 which—

Figure 1 is a perspective view of the puzzle-case embodying the features of my design, the cover being removed; and Fig. 2 is a transverse section through the puzzle-case and its 15 cover.

The invention relates to that class of puzzle-cases in which rolling objects are to travel over a surface of peculiar configuration.

The leading feature of the design consists

in the band-like margin or standing border 20 A and a bed B, to which the band-like border is fitted. The bed in plan and in cross-section has an appearance similar to the frustum of a cone, the inclination being from the apex downward gradually in direction of the border, while at the apex of the border A a dish-like cavity C is formed. The entire upper surface of the bed inclines upward from the border to the said cavity.

The minor feature of the design consists in 30, a cover D for the body.

I claim—

The design for a puzzle-case herein shown and described.

JAMES HIPKINS MCNEILL.
